G. M. TURNER.
SHEET METAL SEATING.
APPLICATION FILED AUG. 15, 1914.

Patented June 26, 1917.

UNITED STATES PATENT OFFICE.

GILES M. TURNER, OF ST. CHARLES, ILLINOIS.

SHEET-METAL SEATING.

1,230,948.

Specification of Letters Patent. Patented June 26, 1917.

Application filed August 15, 1914. Serial No. 856,897.

To all whom it may concern:

Be it known that I, GILES M. TURNER, a citizen of the United States, residing at St. Charles, in the county of Kane and State of Illinois, have invented certain new and useful Improvements in Sheet-Metal Seating, of which the following is a specification.

The object of this invention, generally speaking, is to produce an improved seating device, herein shown as a chair, which is constructed of sheet metal and which is strong and durable, as well as comfortable and pleasing in appearance.

More specifically the invention relates to 15. the construction of the seat, to a detachable upholstered section fitting interchangeably in the seat or the back, and to the means for fastening the covering material of the upholstered sections.

20 In the accompanying drawings, Figure 1 is a front elevation, and Fig. 2 a plan view of a chair having an upholstered seat and back. Fig. 3 is an enlarged fragmental plan view of this chair with parts broken 25 away. Fig. 4 is a vertical sectional view taken on line 4—4 of Fig. 3. Figs. 5 and 6 are fragmental underside views showing the manner of folding the covering material at the corners.

30 In the embodiment of my invention illustrated in the drawings, the seat comprises a stationary rim or open frame 40 to which the legs and back are secured, and an upholstered section fitting in said frame and 35 detachably mounted thereon. This stationary frame of the seat comprises four sides which preferably have horizontal inturned flanges 41 at their lower edges, the flanges overlapping at the corners of the frame and 40 serving to strengthen the frame. In this form of seat the legs 42 lie at the outer sides of the seat and are suitably secured thereto, as by means of bolts 43.

45 The detachable section of the seat fits 45 within the sides of the stationary frame and rests at its corners upon brackets 44 which fit in the corners of the stationary portion and are rigidly secured in place in any suitable manner. The detachable section may 50 be held in place by any suitable means, that herein shown comprising screws 45 passing upwardly through openings in the brackets 44 and threaded into the detachable section.

55 The back of the chair comprises a sta-

tionary rim or open frame 46 which in the present instance has only three sides, the lower side being open and the lower ends of the upright sides fitting against and being rigidly secured to the rear corners of the 60 stationary frame of the seat. The sides of the back frame have inturned flanges like the seat, and inasmuch as the back frame is thinner than the seat, the detachable section of the back may if desired bear against the 65 inturned flanges thereon instead of against brackets like 44 in the seat frame. The detachable back section may be secured in place by screws similar to those of the seat frame.

70 The seat and the back are preferably made of the same size so that the detachable upholstered sections thereof may be used either upon the seat or the back of the chair. This detachable feature is very important to the manufacturer, since it enables him to carry in stock a large assortment of detachable sections of different colors, materials, or the like, without the necessity of carrying a complete chair for each 75 style of upholstery. In filling an order, the style of upholstery desired may be quickly secured to the frame of the chair. Inasmuch as the seat and back are the same size, the 80 number of detachable sections to be carried 85 in stock is minimized, since any section will fit either the seat or the back.

In their preferred form these detachable sections comprise a sheet metal base 48, a flexible covering material 49, such as leather, 90 cloth, or other material, and an intermediate layer of suitable filling or padding material 50. At the edges of the base 48 are angularly extending flanges, and the covering material is carried around these flanges 95 and is held in place by suitable clips which act to draw the covering material taut and secure it firmly to the base.

As shown in Fig. 4 the flange 51 extends 100 downwardly from the base and is turned upwardly as at 52 at its lower edge, the covering material passing downwardly and thence around said upturned edge to conform to the flange. A suitable number of 105 clips 53 of plate-like form, are then placed with the lower edge engaging the cloth in the groove formed by the upturned edge 52 of the flange, and the upper edge of the clip abutting against the cloth in the corner 110 formed by the flange and the edge of the

base 48. The flange may be bent inwardly beyond a right angle, as shown, in order to securely hold the clip in place. One or any suitable number of these clips may be used 5 at each side of the seat. The flange 51, or more strictly speaking, the cloth beneath said flange, bears against the brackets 44 at the corners of the seat and the screws 45 draw the detachable section tightly against 10 said brackets to rigidly secure the seat section to the frame of the chair.

Figs. 5 and 6 illustrate the manner in which the covering material is folded about the corners. The covering material is preferably notched as at 60 to provide a tongue 61 at each corner of the base 48 and the edges of the material adjacent to said tongue are first folded inwardly about the flange 57, the tongue then being folded inwardly 15 over said edges. The clips 59 are then pressed into place to secure the covering material to the base.

While I have herein shown my invention as applied to a chair, it is obvious that certain features are applicable also to other seating devices such as divans, davenports, 25 or the like.

I claim as my invention:

1. A detachable upholstered section for seating devices having, in combination, a sheet metal base having at its edges downturned angular flanges which are turned up at their lower edges, a covering material, the edge portions of which are folded about said 30 flanges and said upturned edges, and clips engaging the covering material in the grooves formed by the upturned edges of the flanges for securing the covering material to the base.
2. A removable section for seating devices having, in combination, a sheet metal base having angular flanges at its edges, a cover- 40

ing material folded about said flanges, the material being notched adjacent to its corners to provide tongues, and the edge of the 45 material adjacent to each tongue being folded inwardly first, and the tongue being then folded inwardly over said edges, and sheet metal clips engaging the material and the flanges for securing the material to the 50 base.

3. An upholstered section for seating devices having, in combination, a sheet metal base with downturned angular flanges at its edges, said flanges being turned upwardly 55 and inwardly at their lower edges, a covering material, the edge portions of which are folded about said flanges and said upturned and inturned edges, and clips engaging the covering material in the grooves formed by 60 the edges of the flanges and in the angle formed by said base and the downwardly projecting flanges.

4. A removable section for seating devices having, in combination, a sheet metal 65 base having angular flanges at its edges, a covering material folded about said flanges, the material being notched adjacent to its corners to provide tongues, and the edge of the material adjacent to each tongue being 70 folded inwardly first, and the tongue being then folded inwardly over said edges, and sheet metal clips engaging the covering material adjacent the edges of the flanges and in the angle formed by the base and 75 the flanges for securing the material to the base.

In testimony whereof, I hereunto set my hand in the presence of two witnesses.

GILES M. TURNER.

In the presence of—
C. PAUL PARKER,
MARGARET H. MANN.

Corrections in Letters Patent No. 1,230,948.

It is hereby certified that in Letters Patent No. 1,230,948, granted June 26, 1917, upon the application of Giles M. Turner, of St. Charles, Illinois, for an improvement in "Sheet-Metal Seating," errors appear requiring correction as follows: In the drawings, strike out Figs. 5, 6, and 7; renumber Figs. "8" and "9" 5 and 6; and that the said Letters Patent should be read with these corrections therein that the same may conform to the record of the case in the Patent Office.

Signed and sealed this 7th day of August, A. D., 1917.

[SEAL.]

F. W. H. CLAY,
Acting Commissioner of Patents.
